UNITED STATES PATENT OFFICE.

AARON ROTHSCHILD AND BENJAMIN SKLEROV, OF NEW YORK, N. Y.

BATHING APPLIANCE.

Application filed March 12, 1928. Serial No. 260,902.

This invention relates to a toilet appliance, more particularly to a toilet appliance useful in connection with bathing and similar bodily hygienic purposes.

5 Our invention has for an object thereof the provision of a toilet appliance in the nature of an electric motor driven reciprocable member, such as a brush or massaging device, which may be used during bathing or similar 10 bodily hygienic operations, involving personal cleanliness, whereby this pleasurable and necessary operation may be quickly and facilely obtained with maximum comfort and efficiency and minimum effort. More particularly, our invention has for an object thereof the provision of a bath room appliance in the nature of a bathing brush, so mounted and electrically operated so that application of a bathing brush to all parts of the 15 body may be accomplished with great facility and ease and maximum effectiveness, the device including a reciprocable brush operating electric motor, universally positionable, to be capable of being guided to all parts of the 20 body, the mounting further including complete isolation of an electric prime mover, such as a motor, so that a brush, sponge or similar cleansing or lathering device may be applied during a copious application and use 25 of water, as while bathing in a tub or shower without danger of rendering inoperative the motor parts. The invention further contemplates the provision of a toilet appliance which may be conveniently used while making 30 one's toilet and bathing for either facilitating the bathing operation involving the cleansing operation by a motor operated, reciprocable bath brush which may be applied with a copious amount of water or one which 35 may be readily applied for operating other body applicators, such as a sponge or massaging device for the invigorating action derived 40 from a vibratory member.

45 Still more particularly, our invention relates to a toilet appliance particularly useful for such personal hygienic purposes as bathing which is electrically controlled, free yet operable while bathing and further easily and comfortably applicable to the body, yet simple and inexpensive to operate and manufacture.

To attain these objects and such further objects as may appear herein or be hereinafter pointed out, we make reference to the accompanying drawing, forming part hereof, in which—

Figure 1 is a perspective view illustrating our device as associated with a bath tub;

Figure 2 is an enlarged view in side elevation, partially in section;

Figure 3 is a section taken on the line 3—3 of Figure 1;

Figure 4 is an enlarged perspective view of a detail.

Making reference to the drawing, our device may best be illustrated as associated with a bath appliance, such as a bath tub, where at some stationary point we provide our appliance generally referred to at 10, supported from a fixed point such as the wall by a 65 bracket 11 and the interposed, universally positionable extension arm 12. This preferably comprises a pair of horizontally disposed arms 13 and 14, and a rearward, vertically disposed arm 15, of substantial L 75 shape, having a downwardly disposed pintle 16, disposed in the bracket 11 and held in frictional pivotal engagement by the nut 17. An extension 18 on the arm 12, having an eyelet 19 is joined to the horizontally disposed 80 portion of the arm 15 by a coiled spring 20. The forward ends of the arms 13 and 14 are connected to the vertical arm 21 by eyelets 22 and 23 and interposed pins 24 and 25, respectively, permitting pivotal movement of 85 the arms 13 and 14, with respect of the arm 21, in a vertical direction. A central shaft 26 is passed through the eyelets 22 and 23, respectively, and held in position for movement with frictional contact by the end spring 90 washers 27 and the cotter pins 28, passing diametrically through the shaft 26. Mounted upon the shaft 26, between the members 22 and 23, there is disposed a bracket 29 arranged for horizontal movement upon the 95 shaft 26. Disposed from the bracket 29 there is provided a flange 30, to which is connected by screw mounting or dovetail connection the housing 31. This housing has, at 100 one end thereof, a centrally constricted portion 32 serving to centrally position a prime mover in the nature of an electric motor 33, positioned so that the one end is centered in the constricted portion 32 of the housing and the opposite end outwardly disposed toward 105 the outer end of the housing. The rotary shaft 34 of the motor is centered within the plate 35 through the orifice 36, in which is disposed a gland packing 37 for purposes which will become apparent as this description proceeds.

110 The extreme end of the shaft 34 is supplied with an end plate 38, upon which is

mounted an eccentric pin 39. This pin extends through a cross head assembly 40 comprising the plate 41, the cross head guides 42 and cross head 43, mounted for reciprocal movement within the guides 42. A screw cap 44 serves to position the cross head assembly and hold the same within the housing against displacement. Reciprocal movement is imparted to the cross head 43 by the eccentric pin 39, which extends into a horizontally disposed slot 45, in the cross head 43. It will be observed that rotary movement of the eccentric pin will serve to impart reciprocating movement to the cross head 43. Mounted upon upon the cross head 43 there is provided an appliance bracket 46 having at one terminal thereof a ball 47. This serves to position a body appliance device such as the brush 48, provided with a ball socket joint 49 engaging the ball 47. A bolt and wing nut 50 serves to position the brush at any predetermined angular position relatively to the ball 47, which is provided with a cross pin 50' engaging a slot of the socket to prevent lateral movement. In use, the prime mover, such as the electric motor 33, is connected with a source of current supply by the conductor 51, passing through the bracket 29 and the hollow arm of the extension 12, connecting to a wall plug or the like at 52.

In operation, with the current suitably turned on, rotation of the electric motor will serve to impart reciprocating movement to the brush or similar body appliance. This may be used while bathing without danger of entry of the water to the housing enclosing the electric motor so that copious amounts of soap and water may be applied while bathing without danger of "shorting" the electric motor. The bracket and extension 12 serves to maintain the motor and housing in any desired, predetermined position without requiring effort on the part of the user to position it wherever desired, to any level or any part of the body, by the universal movement permitted by the appliance.

It will be further observed that though we have described a reciprocating brush useful in bathing purposes as applied to the prime mover, such as the electric motor, such other devices as a sponge, wash cloth or massaging device may be attached thereto, in which event the motor may be operated at any desired speed best suitable for this purpose so that for washing purposes relatively slow speed and vibration will be imparted to the reciprocating member whereas for purposes of obtaining the invigorating action of the vibrator, the movement of the reciprocating member may be shortened and the speed thereof increased.

In this manner it will be observed that we have provided a device which may be simply and facilely applied and used during such hygienic operations as bathing whereby maxi-

mum effectiveness may be obtained with greatest facility, ease and comfort.

Having thus described our invention and illustrated its use, what we claim as new and desire to secure by Letters Patent, is—

1. In a toilet appliance for combination with a bathing device, an electrical prime mover, a housing for said prime mover enclosing the same against ingress of water, means for supporting said prime mover in relatively universal positions, means operable by said prime mover for imparting a reciprocating movement to a body brush.

2. In a toilet appliance for combination with a bathing device, an electrical prime mover, a housing for said prime mover enclosing the same against ingress of water, means for supporting said prime mover, means operable by said prime mover for imparting a reciprocating movement to a body brush.

3. In a toilet appliance for combination with a bathing device, an electrical prime mover, a housing for said prime mover enclosing the same against ingress of water, means for supporting said prime mover, a guide on said housing, a reciprocating member in said guide operable by said prime mover, and means on said member for mounting a body applicator.

4. In a toilet appliance, in combination with a bathing device, an electric motor, a housing for said motor, means connected with said housing for supporting the same in predetermined positions relatively to said bathing device, means on said housing for completely enclosing said electric motor a plate in said housing through which the shaft of said motor extends and means on said plate for rendering said motor inaccessible to water, a guide on said housing and a reciprocating member mounted in said guide and means connected with said shaft for moving said reciprocating member and a body appliance attached to and operated by said reciprocating member.

5. In a toilet appliance, in combination with a bathing device, an electrical prime mover, a housing for said prime mover, means for mounting said housing in predetermined position, said electrical prime mover having the shaft thereof connected for moving a body appliance and means on said housing for enclosing said shaft to prevent ingress of water to the electrical prime mover.

6. In a toilet appliance, in combination with a bathing device, an electrical prime mover, a housing for said prime mover and means for mounting said housing in predetermined position, said housing comprising a constricted portion for centering and positioning a portion of the electrical prime mover, a bearing plate through which the shaft of said motor extends and means on said plate permitting rotary movement of

said shaft to prevent ingress of water comprising a gland packing for said shaft and means on said housing for mounting a movable body appliance device and means on said shaft connected with said body appliance device for imparting movement thereto.

7. In a toilet appliance, in combination with a bathing device, an electrical prime mover, a housing for said prime mover and means for mounting said housing in predetermined position, said housing comprising a constricted portion for centering and positioning a portion of the electrical prime mover, a bearing plate through which the

shaft of said motor extends and means on 15 said plate permitting rotary movement of said shaft to prevent ingress of water comprising a gland packing for said shaft and means on said housing for reciprocally mounting a movable body appliance device and 20 means on said shaft connected with said body appliance device for imparting reciprocal movement thereto.

In witness whereof we have hereunto signed our names this 8th day of March, 1928.

AARON ROTCHILD.
BENJAMIN SKLEROV.
